UNITED STATES PATENT OFFICE.

GEORGE EDMOND WOOD, OF WELLINGTON, NEW ZEALAND, ASSIGNOR OF ONE-HALF TO
CHARLES RICHARD LAMB, OF WELLINGTON, NEW ZEALAND.

STOP FOR SLIDING WINDOW SASHES.

Application filed August 2, 1924, Serial No. 729,830, and in New Zealand September 5, 1923.

This invention relates to sashes and the like, of the type slidable in guides or frames without the aid of balance weights, and wherein spring pressed members and racks 5 are used between the guides or frames and the sashes, for the purpose of holding the latter in any desired raised position.

The object of the invention is to provide improved sash holding and locking means of 10 the aforesaid type.

According to this invention the improved sash stop or holder comprises frames or casings fitted with spring pressed plates slidable to and from the sash, and recessed into the 15 frame or guides in which the sash operates, one at each side of the latter, said slidable plates being provided with rounded projections, which under the action of the springs 20 protrude from the frame or guides, and engage racks recessed in the sash edges.

The springs are made strong enough to keep the rounded projections engaged in the rack so as to hold the sash against downward movement when released after being raised, 25 but are not strong enough to prevent the sash from being moved up or down, as required.

The means for locking the sash against movement either up or down, consists of a flat bar member which is entered in the 30 frame or casing behind the sliding plate therein, and is capable of being turned to prevent movement of the latter, whereby the rounded projections are unable to be moved from engagement in the racks, in the sash, 35 and the latter is thereby locked against up or down movement.

In the accompanying drawing in conjunction with which the invention will be further described:—

40 Figure 1 is an elevation of a window fitted with the improved means.

Figure 2 is a view of portion of an outer vertical edge of a sash, with a rack recessed therein.

45 Figure 3 a vertical sectional view on the line A—A Figure 2.

Figure 4 is a part sectional elevation of a sash and a window frame showing the improved sash holding and locking means fitted 50 thereto.

Figure 5 is a sectional plan view on the line B—B, Figure 4.

Figure 6 is a perspective view of the locking member while

Figures 7, 8 and 9 are sectional elevations 55 and

Figure 10 a part sectional elevation, illustrating modifications.

Each vertical member of a sash 1 has recessed into its outer edge a rack 2, the latter having the formation illustrated in Figures 2 and 3 where it will be seen that the portions 2^a of the rack connecting the deep ends of the recesses 3 with the shallow ends thereof are rounded both where they join 65 the deep ends and where they join the shallow ends, and that said portions 2^a are not at right angles to the sash 1 but slope upwards.

Also the toothed portion of the rack is not 70 of uniform width throughout the length of the latter, but instead said toothed portion has its greatest width at each deep end and from each of the latter the toothed portion tapers downwards to a shallow end, until 75 it joins with the next deep end, where it enlarges again to its greatest width.

The rack therefore has formed therein a series of recesses 3 each of which is deeper and wider at its upper end than at its lower 80 end each of the latter being joined with the wide and deep end of the recesses 3 next below by a rounded and sloped portion 2^a.

The racks 2 extend the full height of the sash, and opposite each of the former there 85 is recessed into the window frame 4, a casing or frame 5, secured therein by screws 5^a (Figure 4).

Each frame or casing 5 has fitted therein a plate 6 slidable to and from the sash 1, 90 said plate having on its outer side rounded projections 6^a the diameter of which is equal to the diameter of the widest or upper ends of the recesses 3 in the racks 2.

The plate 6 is pressed towards the sash 1 95 by springs 7 fitted in the frame or casing 5, said plate being prevented from leaving the latter by the inturned edges or projections 8 on said frame or casing (Figure 5).

When the plate 6 is pressed by the springs 100 7 against the inturned edges or projections 8, the rounded projections 6^a protrude from the window frame 4, a distance equal to the depth of the deepest ends of the recesses 3 in the racks 2.

The springs 7 are made strong enough to keep the rounded projections 6^a in engagement in the recesses 3 of the rack 2, so as to

hold the sash in a raised position after being pushed up and released, but said springs 7 are not strong enough to prevent the racks 2 from being forced past the projections 6^a when it is desired to raise or to lower the sash.

When raising the sash 1, the rounded projections 6^a and plates 6 are forced gradually into the frames or casings 5, by the long slopes from the deep to the shallow ends of the recesses 3, each time one of the latter passes a rounded projection 6^a, but immediately a portion 2^a passes a projection 6^a the latter is forced sharply into the upper or deep end of the following recess 3.

As a rounded projection 6^a is forced out of a recess 3, the part of the former entered in the recess becomes smaller in diameter and each recess 3 is therefore made to taper or to narrow in width downwards as shown in order that no matter how much of a projection 6^a is entered in a recess 3, said projection 6^a will at all times neatly fit the recess, and movement of the sash 1 side ways in the window frame 4 will be prevented. Also the narrowing of the recesses 3 as shown has the effect of keeping the centre of each vertical member of the sash directly opposite or in line with the centres of the rounded projections 6^a, thereby ensuring easy and true running of the sash 1 in the window frame 4.

In order to lock the sash 4 a flat bar member 9 turnable in a plate 10 adapted to be secured to the surface of the window frame 4 inside a building and provided with a handle 11, is inserted in a frame or casing 5 between the sliding plate 6 therein and the back of said frame or casing.

The bar member 9 is of such a width and is so located that upon being turned on to its flat side as shown in Figure 4, it will prevent inward movement of the plate 6 and projections 6^a and owing to the latter being entered in recesses 3, movement of the sash 1 either up or down will be prevented.

The opening 10^a through which the bar member 9 is inserted in the frame or casing 5, contains a stop 11^a which prevents the bar member 9 from being given more than a quarter turn which is all that is required, either to lock or to unlock the sash 1.

When upper and lower sashes 1 are fitted in a window frame 4 as in Figure 1 the frames or casings 5 for the lower sash are fitted in the window frame near the top of the lower sash, while the frames or casings 5 in respect of the upper sash are fitted in the window frame near the bottom of said upper sash. These positions are necessary in order to enable the sashes 1 to be moved as far as possible without becoming disengaged from the projections 6^a.

Only one locking bar member 9 need be provided in respect of each sash, and said

bars 9 are cross grooved at intervals as at 9^a, in order that they may be broken off and made a length to suit the particular frame in which they are being fitted.

Instead of the projections 6^a being made integral with the plate 6 as shown in Figures 4 and 5, they can consist of balls 12 held in sockets 13 on said plate, see Figure 7.

Also in a further form the projections 6^a can consist of round nosed plungers 14 adapted to be forced through a fixed plate 15 on the frame or casing 5 by springs 16 the latter surrounding stems 14^a on the plungers and being housed in cups 17, which when the plate 6 is forced forward by turning the locking bar member 9, engage behind the plungers 14 and prevent the latter from being moved into the frame or casing 5.

In the form shown in Figure 9 the plungers 14 are without stems and with the springs 16 work in the cups 17, pins 18 from said plungers being entered in slots 19 in the cups 17.

The slots 19 are long enough to permit the necessary movement of the plungers 14 in the cups 17 as the sash 1 is raised or lowered, but when the bar member 9 is turned to its locking position it forces the plate 6 towards the sash 1 and brings the inner ends of slots 19 up against the pins 18 thereby preventing backward movement of the plungers 14 and effecting the locking of the sash.

In the form shown in Figure 10 the sliding plate 6 has secured thereto a corrugated strip 20 adapted to engage and work in a correspondingly corrugated strip 1 recessed in the edge of the sash in a manner similar to a strip 2.

When raising a sash 1 fitted with the form of rack illustrated in Figures 2 and 3, the gradual forcing inwards of the rounded projections 6^a or the plungers 14 by the long slopes of the recesses 3 has the effect of considerably easing the raising of the sash, as in the latter operation the weight of the latter has to be considered.

When the sash is released while in a raised position the engagement of the projections 6^a or the plungers 14 below the steeper or sloped portions 2^a of the rack under the action of the springs is responsible for the sash being held in its raised position.

The operation of lowering the sash, when the sharper or sloped portions 2^a required to be forced past the rounded projections 6^a or the plungers 14, is comparatively easy owing to the movement being downwards, and to the fact that the weight of the sash assists the operation.

What I do claim and desire to obtain by Letters Patent of the United States of America is:—

1. Stop means for window sash and the like, comprising, a recessed slidable member to be vertically positioned, a rack in the re-

30

35

40

45

50

cess, a fixed member slidably receiving the
slidable member, resiliently controlled de-
tent means carried by the fixed member and
coacting with the rack, the rack comprising
5 a strip of material having alternate wide and
narrow socket and projection portions, the
portions of strip connecting each socket to
the projection thereabove, being shorter and
at a greater angle to the vertical, than the
10 portions connecting the sockets to the pro-
jections therebelow, said shorter portions
which have greater angularity to the verti-
cal engaging the upper sides of said detent
upon descent of said recessed slidable mem-
15 ber, said detent thereby partially supporting
the weight of said slidable member.

2. Stop means for window sash and the
like, comprising, a recessed slidable member
to be vertically positioned, a rack in the re-
20 cess, a fixed member slidably receiving the
slidable member, resiliently controlled de-
tent means carried by the fixed member and
coacting with the rack, the rack comprising
a strip of material having alternate wide
25 and narrow socket and projection portions,
the plunger means including a plate posi-
tioned opposite the rack, resilient means

biasing the plate toward the rack, and
rounded detents on the plate and contacting
with the rack.

3. Stop means for window sash and the
like, comprising, a recessed slidable member
to be vertically positioned, a rack in the re-
cess, a fixed member slidably receiving the
slidable member, resiliently controlled de-
tent means carried by the fixed member and
coacting with the rack, the rack comprising
a strip of material having alternate wide
and narrow socket and projection portions,
the plunger means including a plate posi-
tioned opposite the rack, resilient means
biasing the plate toward the rack, and
rounded detents on the plate and contacting
with the rack, the detents being integral
40 with the plate, a casing mounted in the fixed
member and slidably receiving the plate,
pins carried by the casing, springs sleeved
on the pins and bearing against the plate,
and means for positively locking the plate
against movement with its detents bearing
45 against the rack.

In testimony whereof I have signed my
name to this specification.

GEORGE EDMOND WOOD.
